ANALYSIS OF VARIANCE

584
Richard Oliver, Attorney

UNITED STATES PATENT OFFICE.

CHARLES I. WILLIAMS, OF UTICA, NEW YORK.

PUMP.

Application filed June 29, 1925. Serial No. 40,358.

This invention appertains to a novel fuel feeding device for the carbureters of internal combustion engines and the primary object of the invention is to provide automatic means for controlling the supply of gasoline to a chamber for the carbureter from a supply tank, said means being so constructed as to normally maintain the gasoline at a constant level in the chamber.

10 A further object of the invention is to provide a chamber for supplying gasoline to a carbureter having novel means mounted therein for automatically controlling the level of the gasoline in the chamber, the 15 chamber having a suction pipe connected with the upper end thereof for communication with the intake manifold of the engine, a feed pipe leading from the supply tank of the gasoline and an atmospherical communication, means being provided for automatically shutting off the atmospherical communication and for opening up communication with the suction pipe, whereby the gasoline in the chamber will be held in a constant level.

20 A further object of the invention is the provision of a single float for controlling the communication of the chamber with the atmosphere and the suction pipe.

25 A further object of the invention is to provide novel means for permitting the connection of the chamber directly with a carbureter, thereby eliminating the necessity of placing the chamber at a remote point from the carbureter, as now contemplated in vacuum feed devices for internal combustion engines.

30 A still further object of the invention is to provide a novel fuel control device of the above character which will insure a positive quick starting and stopping device which causes the level of the fluid in the float chamber to be practically maintained at a constant level, and which is so constructed 45 as to eliminate the necessity of priming the float chamber, when the gasoline supply tank and float chamber have been once emptied and the supply tank refilled.

35 A still further object of the invention is to provide an improved device of the above character, which will be durable and efficient in use, one that will be simple and easy to manufacture and one which can be placed upon the market at a small cost.

With these and other objects in view, the 55 invention consists in the novel construction, arrangement and formation of parts, as will be hereinafter more specifically described, claimed and illustrated in the accompanying drawings, in which drawings:

60 Figure 1 is a vertical section through the improved fuel control device showing the same applied to a conventional type of carbureter,

65 Figure 2 is a horizontal section through the same taken on the line 2-2 of Figure 1 looking in the direction of the arrows,

70 Figure 3 is a detail perspective view illustrating the means for controlling the atmospherical communication of the float chamber,

75 Figure 4 is a perspective view illustrating the means for controlling the communication of the float chamber with the suction pipe.

80 Referring to the drawings in detail, wherein similar reference characters designate corresponding parts throughout the several views, the letter A generally indicates the improved fuel control device or pump and B a conventional carbureter, which can be considered as the "Holly" type.

85 As shown the carbureter B includes the usual mixing chamber 5 having formed on its lower end a reduced body 6 provided with the axial bore 7, the lower end of which terminates in an angularly extending passageway 8 for communication with the ordinary bowl of the carbureter (not shown). In the larger types of carbureters, a check valve of conventional form is placed in the passageway 8. The upper end of the extension 9 is provided with a needle valve seat 9 for controlling the flow of the gasoline into the mixing chamber 5 and this valve seat is adapted to have cooperating therewith a needle valve 10 which extends entirely through the mixing chamber and out the upper end thereof. The upper end of the needle valve can be provided with a suitable manipulating handle or knob 11. The carbureter is provided with the usual means 100 for communication with the intake manifold air inlets and the like.

105 The fuel feeding device A embodies a chamber or bowl 15 which includes the circular side wall 16 and the flat bottom wall 17. This bowl can be secured at its upper end to a flange 18 carried by the carbureter 5. This flange forms a top wall for the

chamber. The extension 6 of the carbureter can be provided with a suitable stud 19 which can extend axially through the bottom wall 17 of the chamber and a suitable nut 20 can be threaded on the stud in engagement with the bottom wall.

It is to be noted at this point that the angular way 8 of the carbureter communicates with the chamber 15 adjacent to the lower end thereof.

Extending into the upper end of the chamber is the fuel supply pipe 21 which extends directly from the ordinary supply tank for the carbureter. A suction pipe 22 also communicates with the upper end of the bowl at one side thereof and this pipe leads directly to the intake manifold of the internal combustion engine, so that a constant suction will take place through the pipe during the operation of the engine. The lower end of the suction pipe is provided with an angular extension 23 which extends into the chamber and the lower end of this pipe is solid or closed in any suitable manner, and an angularly extending way 24 opens out through one side of the pipe and communicates with the bore of the said pipe. This angular way is spaced below the top wall or flange 18 of the chamber.

In accordance with this invention, a stud 25 is extended through the top wall or flange 18 of the chamber at a point diametrically opposite the point of connection of the suction pipe with the chamber and this stud 25 is provided with an axial bore 26 having its lower end terminating in a radially extending way 27 which communicates with the interior of the chamber. This stud permits atmospherical communication to be had from the interior of the chamber.

In order to control the level of the gasoline within the chamber, a float 30 is provided. This float 30 is of annular construction and surrounds the extension 6 of the carbureter and can be formed in any way and of any desired material, such as cork.

Secured to the upper surface of the float 30 at diametrical opposite points are sleeve valves 31 and 32. These sleeve valves 31 and 32 are provided respectively for controlling the atmospherical communication of the chamber with the exterior of the chamber and the communication of the chamber with the suction pipe 22 and these sleeves slidably receive respectively the stud 25 and the angular end 23 of the said suction pipe. As shown the lower ends of the sleeves 31 and 32 are provided with walls 34 and suitable fastening elements such as bolts or screws 35 are passed through the float and into the walls 34 for retaining the sleeve valves in position. The sleeve valve 31 is provided with a port 36, which is adapted to communicate with the radially extending way 27 when the float is in its raised position.

tion which establishes communication with the atmosphere from the interior of the chamber. The upper end of the sleeve valve 32 is provided with a notch 37 which is adapted to communicate with the port or way 24 when the float is in its lowered position for permitting the suction pipe to communicate with the interior of the chamber. It is obvious that when the float is in its lowered position that communication with the atmosphere is prevented in view of the fact that the port 36 will be positioned below the way 27. The upward movement of the float 30 beyond a predetermined point is limited by the sleeve valves 31 and 32 which engage the flange or top wall of the chamber and downward movement of the float is limited beyond a predetermined point by a radially extending pin 38 secured to the extension 6 of the carbureter. This pin 38 insures the proper alining of the notch 37 with the way 24 when the float is in its extreme lowered position.

In operation of the improved device, it can be seen that when the chamber is filled to a predetermined level as shown in Figure 1, the float will be in a raised position and thus communication with the suction pipe 22 will be cut off, while atmospherical communication is had by means of the bore 26, way 27 and port 36. However when the level of the gasoline falls, the float will lower and the sleeve valves will slide downward on the stud 25 and the extension 23 of the pipe shutting off communication with the way 27 and establishing communication with the suction pipe 22. The suction to the pipe 22 will suck in the gasoline from the supply pipe 21 into the chamber and when the sufficient amount of gasoline has been supplied to the chamber the float will again rise, so as to shut off communication with the suction pipe and again establish communication with the atmosphere. The gasoline is taken in the usual manner from the chamber to the carbureter through the bore 7 and way 8 of the extension 6.

Changes in details may be made without departing from the spirit or scope of this invention, but:

What I claim as new is:

1. In a device of the class described, the combination of a chamber having communication with a fuel supply pipe, a suction pipe and the atmosphere, the suction pipe extending into the upper end of the chamber and having a radially extending bore, the atmospherical communication including a stud extending into the upper end of the chamber having an axial bore communicating with the atmosphere and a radially extending bore communicating with the chamber, a float mounted within the chamber, and sleeve valves secured to the upper face of the float slidably receiving the stud and the part

of the suction pipe extending into the chamber, the valves being provided with ports for communication at different times with the port in the stud and a port in said suction pipe.

2. In a device of the class described, the combination of a chamber provided with a top wall having independent and separate connections with a fuel supply pipe, a suction pipe and the atmosphere, the suction pipe having an angular end extending through the top wall into the chamber at one side thereof having a bore and a radial way communicating with the chamber, the 10 atmospherical communication consisting of a stud extending through the top wall into the chamber having an axial way and a radially extending way, the axial way communicating with the atmosphere and the radial way 15 with the chamber, the stud being arranged at a diametrically opposite point from the supply pipe, a float arranged in the chamber, means for limiting the downward movement of the float, sleeve valves arranged on the upper 20 surface of the float at diametrically opposed points for slidably receiving the stud and the angular extension of the suction pipe, the valves being arranged with ports disposed in different planes, and fastening 25 elements extending through the float into 30 said valves for holding the same on the float,

the valves engaging the top wall for limiting the upward movement of the float.

3. In a device of the class described, the combination with a mixing chamber having an extension formed on the lower end thereof provided with an axial way communicating with the chamber, the extension being provided with a radial way, a fuel chamber receiving the extension, a needle 35 valve for controlling the flow of fuel from the fuel chamber to the mixing chamber, the chamber having independent and separate connections with a fuel supply pipe, a suction pipe and the atmosphere, a float in the 40 fuel chamber surrounding the extension, means carried by the extension for limiting the downward movement of the float, and sleeve valves carried by the upper surface 45 of the float for controlling the last two connections, the sleeve valves being adapted to limit the upward movement of the float.

4. A device of the character described comprising a bowl, a fuel pipe communicating therewith, valves depending into the 50 bowl and spaced from each other, and sleeves directly attached to the float and having direct sliding engagement with the valves to alternately open and close the same in the 55 movement of the float.

In testimony whereof I affix my signature.
CHARLES I. WILLIAMS.
